UNITED STATES PATENT OFFICE

2,558,801

CARTRIDGE BELT FEEDING MECHANISM

Edwin H. Waitke, Los Angeles, Calif.

Original application December 15, 1943, Serial No. 514,359, now Patent No. 2,410,848, dated November 12, 1948. Divided and this application June 20, 1946, Serial No. 677,948

8 Claims. (Cl. 89—33)

(Granted under the act of March 3, 1883, as amended April 30, 1928; 370 O. G. 757)

1

The invention described herein may be manufactured and used by or for the Government for governmental purposes, without the payment to me of my royalty thereon.

This invention relates to a cartridge belt feeding mechanism for a multi-barrel machine gun of the reciprocating breech block type.

An object of the invention is to provide a cartridge belt feeding mechanism that will be capable of feeding cartridges to a machine gun operable at a high rate of speed.

Another object of the invention is to provide a mechanism that operates in synchronism with the operation of a rapidly moving breech block, to quickly and accurately position each cartridge adjacent its barrel.

A further object of the invention is to provide a mechanism that is simple in construction and durable in operation, and having a minimum number of parts.

Other objects and advantages of the invention will be apparent during the course of the following description.

This application is a division of my copending application Serial No. 514,359, filed December 15, 1943, for a Multiple Barrel Machine Gun, now Patent 2,410,848 dated November 12, 1946.

In the accompanying drawings, forming a part of this specification, and in which like numerals are employed to designate like parts throughout the same.

Figure 1 is a horizontal longitudinal sectional view of a gun equipped with my belt feeding mechanism, taken on the line 1—1 of Figure 2.

Figure 1a is a similar view of the forward continuation of the gun, taken on the line 1a—1a of Figure 2a.

Figure 2 is a vertical longitudinal sectional view thereof, taken on the line 2—2 of Figure 1.

Figure 2a is a similar view of the forward continuation of the gun, taken on the line 2a—2a of Figure 1a.

Figure 3 is a vertical transverse sectional view, taken on the line 3—3 of Figure 1.

Figure 4 is a similar view taken on the line 4—4 of Figure 2a.

Figures 5, 6, 7, 8 and 9 are fragmentary transverse sectional views showing the progressive advancement of the cartridge belt during several recoil and counter-recoil strokes of the breech block.

Figure 10 is a fragmentary perspective view of the slide plate, and

Figure 11 is a perspective view of one cartridge clip, with the belt in dotted lines.

2

The construction and operation of the present invention and associated parts are identical with those disclosed in my patent, herein before identified, and for convenience of reference the same characters will be used to designate like parts in the present application.

Referring now to the drawings, wherein for the purpose of illustration, a preferred embodiment of my invention is shown, the numeral 1 designates the receiver of the gun, having a front plate 2 secured to it by screws 2', Figure 1. This plate has four circular openings 3 for the passage of the breech portions of four identical barrels 4, which are threaded into the receiver as at 5, Fig. 2. The muzzle ends of the barrels are provided with a stationary barrel-brace 6 which has preferably integral therewith, four parallel cylinders 7, through which the barrel ends extend. The barrels are preferably slightly reduced in diameter at their muzzle ends as at 8, Fig. 1a, forming shallow shoulders 8' against which the rear ends of the cylinders 7 abut. Threaded portions 9, of the barrels receive knurled nuts 9' that are screwed against the forward ends of the cylinders and serve to firmly secure the barrels to the stationary barrel-brace, of which the cylinders form an integral part.

There are four bores 10 (see Fig. 2a) in the body of the barrel-brace, each in communication with a barrel bore through gas ports 10' which register with short radial conduits 10'' in the forward end of the barrel-brace 6. There is a bore for each barrel, and parallel with each barrel, and each bore contains a long piston 11, each one of which is secured at its rear end to a connector-head 12, common to all the pistons. The bores 10 are of such length as to accommodate the pistons, and at the same time provide gas chambers 116 (Fig. 2a) for receiving the gas for moving the pistons and the parts actuated thereby. The normal position of the head 12 is against the rear end of the stationary barrel-brace 6, with the pistons inside the brace. The foregoing description covers certain details of a gun disclosed in my patent, hereinbefore identified, and are not a part of the present invention, being merely used for the purpose of illustrating one application of the invention. For example a single piston could replace the four pistons and the gun would work, minus the additional features disclosed in my co-pending application.

Two identical laterally extending arms 13 (Fig. 1a) are integral with the rear end of the stationary barrel-brace 6, and in their extremities 55 are oscillatably mounted oppositely disposed

parallel belt-feed-rods 14, of which there are two, each provided with a helical cam groove 15. The hubs 16 of a reciprocable cross head 17, surround the rods 14, and pins 18 secured in the hubs enter the grooves 15 to cause oscillation of the rods during reciprocation of the cross head. The cross head 17 is always against the rear face of the connector-head 12, it being held there by a breech-block drive rod spring 31 as will more fully appear.

The belt-feed-rods 14 extend rearwardly for a considerable distance beyond the front end of the receiver, and their rear ends have bearings in brackets 18' mounted on identical side plates 19, that close the feed slots in the sides of the receiver and house important mechanism that will now be described.

The rear end of each rod carries a pinion 20 arranged to engage racks 21 of identical feed slides 22, mounted for simultaneous vertical movement inside the said housing plates, and within the recesses or guideways 120 of the receiver 1.

Mounted for reciprocation within the receiver 1 is a breech block 23 having a drive rod 24 secured thereto. At its forward end the drive rod is secured centrally to the cross head 17. The helical spring 31 surrounds the breech block drive rod 24 and is interposed between the cross head 17 and the face of a vertical boss 32, integral with the front face of the front plate 2 of the receiver. This spring returns the breech block to battery position and normally holds the cross head 17 against the connector head 12, and consequently returns the cross head to its forward position.

Adjacent the upper and lower front corners of the breech block, are pivoted four cartridge feed pawls 43, the pawls being pivoted in recesses in which are springs 44, acting upon the pawls to keep them normally slightly extended beyond the lateral edges of the breech block in position to engage their appropriate cartridge to force them out of their clips and into the appropriate chamber in the barrel, as the breech block moves forward.

The upper and lower laterally extending portions of the breech block are provided respectively with downwardly opening grooves 45, and similar upwardly opening grooves 46, for the passage and guidance of four identical ejector rods 47 and 48, secured to the receiver, the arrangement being such that the heads of all the cartridge shells will be simultaneously engaged on their inner edges when the breech block 23, with its extracted shells, has moved rearwardly sufficiently to have fully extracted the shells from the cartridge chambers. This engagement between the ejectors and the shell heads will forcefully tilt the shells and eject those from the upper barrels out of upper receiver openings 50, and those from the lower barrels downwardly through lower openings 51 of the receiver.

As hereinbefore shown, there are two belt-feed-rods rotatably mounted in the ends of the laterally extending arms 13 of the stationary barrel-brace 6, each having a helical cam groove 15 entered by a pin 18 in the hubs 16 of cross head 17, through which hubs the rods slidably pass so that oscillatory movement is given the rods upon reciprocation of the cross head, which through pinions 20, engaging racks 21 on oppositely disposed feed slides 22, causes the vertical reciprocation of said slides. The slides move vertically in the recesses or guideways 120, in the sides of the receiver. The feed slides and

cartridge belts are identical and description of one will serve for both. The slide (Figure 10) comprises a plate 121, having a central vertical recess 122 for the reception of the rack 21 which may be secured to the plate by short screws 123. The plate has a rectangular opening 124 in its upper portion to make a clearance for a resilient feed pawl 125, whose upper end is fastened, by any suitable means, in a recess similar to the recess 122 that receives the rack.

The cartridge belt (see Figure 11) comprises a strip 126 of suitable flexible material, to which is attached at appropriate intervals, sufficiently resilient metallic clips 127 having lips 128 to grip the cartridges, and tabs 129 that are bent sharply around the flexible strip to fasten the clips to the flexible strip 126. The upper edges of the bent tabs form a long shoulder 130, engaged by the lower edge of the feed-pawl 125 upon the downward movement of the feed slide, to feed the cartridges when the slide is operated in feeding direction, by the belt-feed-rod. The two slides are operated in unison as the feed rods are oscillated, and the slides are so timed and the cartridges are so positioned on the belt, that alternate pairs of cartridges on each belt are fed to the barrels on every downward movement of the slides. For instance, as seen in Figs. 5, 6, 7, 8 and 9, upon the downward movement of the slide, the cartridges *a* will be fed to the upper barrels and the cartridges *b* to the lower barrels, the belt moving the distance of two cartridge spacings upon each downward movement. By feeding the belt a distance of two cartridges spacings on each reciprocation of the feed slide it is possible for the cartridges to be placed close together, and at such distances that the feed pawls 43 on the receiver, will strip off alternate cartridges from the belt. Thus both upper and lower barrels on one side of the gun are fed from the same belt.

When the cartridges reach the levels of the barrel bores, they are forced forward by the cartridge feed pawls 43 on the breech block, and stripped from their clips, which sustain them both laterally and longitudinally until their projectile ends engage the inclined walls 131 of the receiver, when a further movement of the breech block will force them simultaneously into the cartridge chambers of the barrels.

The operation of the feed mechanism is as follows:

The cartridge belts, suitably supported from above the receiver, are placed in the receiver in position to be further fed by the feed slides. The first group of cartridges are fed to their respective barrels by a hand charging means fully described in my aforesaid patent.

The rearward movement of the breech block drive rod 24 will cause the cross-head 17 to rotate the belt feed rods 14, which will, through pinions 20, operate the cartridge feed slides 121 downward to feed the cartridges to position to be engaged by the cartridge feed pawls 43. On the forward movement of the breech block, the pawls simultaneously engage the four cartridges and strip them from their clips, and the breech block travelling further forward will force the projectile ends of the cartridge against the inclined walls of the receiver, where the cartridge will be deflected into the chambers of the barrels. The gun may then be fired, and will continue as long as it is permitted to, during which time the belt feed mechanism will continue to feed the cartridge belt to proper position.

Upon firing the gun, gas is admitted simul-

aneously through ports 10' and conduits 10" to all of the bores 10, in which the pistons 11 simultaneously reciprocate. The rear ends of the pistons are secured in the connector-head 12 and will force the connector-head 12 rearwardly against the cross-head 17, when gas from the barrel bores is received in the chambers 113. During this movement of the cross-head, the pins 18 riding in the helical cam grooves 15, of rods 14 cause the cartridge belt to be fed downward.

On counter-recoil stroke of the breech block the breech block drive spring 31 forces the block, its drive rod 24 and the cross head 17 forwardly and by the reverse movement of the pins 18 riding in the helical grooves 15, the rods 14 are oscillated to raise the feed slides 22 to a position to engage another cartridge clip.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus described my invention, I claim:

1. In a cartridge belt feeding mechanism for a multi-barrel machine gun provided with a receiver having recesses, a plurality of barrels fixedly mounted in the receiver, and a breech block reciprocable in said receiver and common to all the barrels, said mechanism comprising a stationary member attached to the barrels in advance of the receiver, belt feed rods journaled at their respective ends in said member and receiver, vertically reciprocable belt feed slides in the receiver recesses each slide being provided with a rack, a pinion fixed on each feed rod engaging a respective rack whereby when the pinions are oscillated, said slides will be reciprocated, and connections between the breech block and said rods, said connections comprising a breech block drive rod fixed to the breech block, at one of its ends, a cross-head fixed to the other end of said rod, and means on said cross head for oscillating said feed rods in response to reciprocation of said breech-block.

2. In a cartridge belt feeding mechanism for a machine gun provided with a receiver having vertically disposed recesses, barrels fixedly mounted in the receiver, and a breech block reciprocable in the receiver, said mechanism comprising a stationary member attached to the barrels in advance of the receiver, reciprocable means including a crosshead connected with the breech block for movement therewith, means carried by the stationary member for driving the reciprocable means and the breech block in recoil movement, belt feed rods passing through the crosshead and oscillatably mounted in the stationary member, vertically reciprocable belt feed slides in the receiver recesses each provided with a rack, pinions on the feed rods engaging the racks, there being helical grooves in the feed rods, and pins in the crosshead of said reciprocable means for engagement with the helical grooves whereby the feed rods and their pinions are oscillated when the breech block is reciprocated.

3. In a cartridge belt feeding mechanism for a machine gun provided with a receiver having recesses, spaced barrels fixedly mounted in the receiver, and a breech block reciprocable in said receiver, said mechanism comprising a stationary member attached to the barrels in advance of

the receiver, reciprocable means including a crosshead connected with the breech block for movement therewith, gas operated means carried by the stationary member for driving the reciprocable means and the breech block in recoil movement, belt feed rods journaled in the stationary member and in the receiver, vertically reciprocable belt feed slides in the receiver recesses each provided with a rack, pinions on the feed rods engaging the racks, means carried by said slides for advancing the belt to present a cartridge to each barrel and means operated by reciprocation of said crosshead to oscillate said rod and pinions to thereby advance the slide a distance equal to two thirds of the distance between the barrels whereby alternate cartridges will be positioned opposite one barrel, while the remaining cartridges will be positioned opposite the other barrel.

20 4. In a cartridge belt feeding mechanism, the combination with a pair of barrels and a gun provided with a receiver having recesses formed therein, two cartridge carrying belts to be fed through the receiver recesses, a single breech block reciprocable in said receiver, said mechanism comprising a stationary member attached to the barrels in advance of the receiver, gas operated means within the stationary member for driving the breech block in recoil movement, and spring driven means between the receiver and the gas operated means for driving the breech block in counter-recoil movement, belt feed rods oscillatably mounted in the stationary member and having helical cam grooves formed therein, a crosshead carried by the spring driven means and having interengaging connections with the cam grooves in the feed rods whereby when the breech block is reciprocated the feed rods will be oscillated, a vertically reciprocable belt feed slide in each receiver recess adjacent the cartridge belt, pawls carried by the feed slides for engaging and advancing the cartridge belts, a rack carried by each slide, and a pinion on each feed rod engaging its respective rack whereby when the feed rods are oscillated the slides and their pawls will be reciprocated to advance the cartridge belts.

5. In a cartridge belt-feeding mechanism for a gun having a receiver, a barrel, and a breech-block reciprocable in said receiver, said mechanism comprising a belt feed rod having a helical groove therein, means journaling said rod in parallel adjacent relation with said barrel, a belt feed slide reciprocable in said receiver transversely of said rod, a rack on said slide, a pinion fixed on said rod in mesh with said rack, means on said slide to engage and advance a cartridge belt through said receiver, and means to oscillate said rod in timed relation with reciprocation of said breechblock, said means comprising a crosshead slidable on said rod and having a pin engaging said helical groove, a rigid connection between said crosshead and said breechblock, and means responsive to gas pressure in said barrels for reciprocating said crosshead and breechblock and thereby oscillating said rod.

6. In a multi-barrel automatic gun, a receiver having vertically-disposed cartridge belt passageways in its right and left sides, right and left pairs of vertically superposed barrels fixed in said receiver, a single breechblock in said receiver and reciprocable therein to simultaneously feed shells from said belts into all said barrels, a belt feed slide vertically reciprocable in each said passageway, detent means carried by each slide to engage and advance a respective belt through

said passageway, a rack on each slide, a pair of rods journaled on the right and left sides, respectively, of said receiver, each said rod having a helical groove therein, a pinion fixed on each rod and in mesh with a respective rack, a crosshead reciprocable along said barrels and rigidly connected with said breechblock and having right and left apertures through which said rods may slide, pins fixed in said crosshead, each engaging a respective groove in said rods, and means powered by gas pressure engendered by firing of said gun to reciprocate said breechblock and crosshead.

7. A gun as recited in claim 6, the bore axes of each pair of barrels being vertically spaced equal predetermined distances, successive clips on said belts being spaced one-third of said distance, each said detent means acting to advance its belt two-thirds of said distance for each reciprocation of said breechblock, whereby alternate cartridges of each belt are presented to the corresponding upper barrel while the remaining cartridges are presented to the corresponding lower barrel.

8. The combination with an automatic gun having two parallel barrels having their bore axes spaced a predetermined distance, a receiver and a single breechblock reciprocable to simul-

5 taneously ram cartridges into the breech chamber of both said barrels, of a cartridge belt having successive cartridge clips spaced one-third of said predetermined distance, and means operated by reciprocation of said breechblock in response to firing of said gun to advance said belt through said receiver two-thirds of said predetermined distance to successively present and load the cartridges in alternate clips into one
10 said barrel and to successively present and load the cartridges in the remaining clips into the other said barrel.
